UNITED STATES PATENT OFFICE.

CARL HOUBEN, OF SAARBRÜCKEN, GERMANY, ASSIGNOR TO EHRHARDT & SEHMER, GESELLSCHAFT MIT BESCHRÄNKTER HAFTPFLICHT, OF SCHLEIFMÜHLE, NEAR SAARBRÜCKEN, GERMANY.

CYLINDER FOR GAS-ENGINES AND THE LIKE.

No. 896,543.

Specification of Letters Patent. Patented Aug. 18, 1908.

Application filed February 2, 1905. Serial No. 243,873.

To all whom it may concern:

Be it known that I, CARL HOUBEN, engineer, a subject of the Emperor of Germany, and residing at 10 Schlossplatz, Saarbrücken, Germany, have invented a new and useful Improved Cylinder for Gas-Engines and the Like, of which the following is a specification.

The present invention relates to an improvement in the cylinders of gas-engines and the like.

The raising of the pressure which has recently taken place in the case of gas-engines and the like, demands more and more strength on the part of the working cylinders of these machines, and it is difficult to manufacture cylinders of somewhat large diameter for large gas-engines, which, in the presence of explosion-pressures of 20-25 atmospheres, 20 possess sufficient strength and durability.

It is necessary to give to the working cylinders walls of unusually great thickness to withstand the maximum pressure of the gases, whereas the cooling jacket cast in one 25 piece with the working cylinder, requires a wall of only slight thickness. On account of this unequal distribution of the iron in the double cylinder, internal stresses arise in the same which, on the cooling of the casting, or 30 during the use of the finished cylinder, not infrequently cause the formation of cracks.

The object of the present invention is to manufacture the cylinder with cooling jacket free from internal stresses by giving to the 35 inner working cylinder and to the outer cooling jacket, walls of equal or approximately equal thickness.

A cylinder with cooling jacket, according to the present invention is illustrated in the 40 accompanying drawing, in which

Figure 1 is a longitudinal section of the same, and Fig. 2 a cross-section.

As shown in the drawing, the inner cylinder *a* has a wall, the thickness of which is 45 less than that corresponding to or less than under ordinary circumstances would be necessary to withstand the highest working pressure, whereas the cooling jacket *b* is formed with a wall having a thickness greater 50 than that corresponding to or necessary to withstand the ordinary pressure to which a cooling jacket is subjected, so that it consequently possesses a surplus of strength. In order to render this surplus of strength

useful for the strengthening of the working 55 cylinder, the space between the working cylinder and the cooling jacket is traversed by water under pressure, which water both cools the cylinder walls and also, in consequence of its small amount of compressibility, 60 transmits as a rigid body so to speak, all excess strain upon or yielding of the inner cylinder to the strong cooling jacket, and consequently the excess material and consequent reserve strength of the outer cylinder 65 is rendered useful for the reinforcement of the inner cylinder. In order to effect this transmission of pressure in the highest degree, it is of course important that neither air nor any other elastic gas be present in the cooling 70 chamber. This is provided for by supplying the cooling water to the cooling chamber from below at the place *c*, and by leading it off from the highest places *d d'* in order that a collection of air and gas bubbles in the cool- 75 ing chamber may be avoided.

What I claim as my invention, and desire to secure by Letters Patent, is:

1. A cast cylinder for gas engines and the like comprising an internal working cylinder 80 having walls of a strength less than the designed maximum stress, an outer jacket with walls of substantially the same thickness as the working cylinder, and an intermediate space for a practically incompressible liquid. 85

2. A cast cylinder for gas engines and the like comprising an internal working cylinder having walls of a strength less than the designed maximum working pressure of the gas, 90 an outer jacket with walls of substantially the same thickness as the working cylinder, and means for supplying a practically incompressible cooling medium at the lower portion of the space between the said walls and for withdrawing the same at the upper portion 95 of said space.

3. A cast cylinder for gas engines and the like comprising an internal working cylinder having walls of a strength less than the designed maximum working pressure of the gas, 100 an outer cooling jacket having walls of a reserve strength at least equal to the deficit in the working cylinder walls, and means for supplying to the space between said walls a practically incompressible cooling medium. 105

4. A cast cylinder for gas engines and the like comprising an internal working cylinder having walls of a strength less than the de-

signed maximum working pressure of the gas, an outer cooling jacket with walls of substantially the same thickness as the working cylinder, the reserve strength of the jacket walls being at least equal to the deficit in the working cylinder walls, and means for supplying under pressure a practically incompressible cooling medium at the lower portion of the space between said walls and for with-

drawing the same at the upper portion of said space. 10

In testimony whereof I have signed my name to this specification in the presence of two subscribing witnesses.

CARL HOUBEN.
